UNITED STATES PATENT OFFICE.

ISADORE BEHRSTOCK, OF LOS ANGELES, CALIFORNIA.

DESIGN FOR A STONE SETTING.

Application filed May 13, 1925. Serial No. 13,421. Term of patent 14 years.

To all whom it may concern:

Be it known that I, ISADORE BEHRSTOCK, a citizen of the United States, residing at Los Angeles, in the county of Los Angeles and State of California, have invented a new, original, and ornamental Design for Stone Setting, of which the following is a specification, reference being had to the accompanying drawing, forming a part thereof.

In the drawing, Fig. 1 is a front elevation of the stone setting, and Fig. 2 is a side elevation of Fig. 1, showing my new design.

I claim:

The ornamental design for a stone setting, as shown.

ISADORE BEHRSTOCK.
